UNITED STATES PATENT OFFICE.

WILLIAM H. GRAHAM, OF ST. LOUIS, MISSOURI, ASSIGNOR TO THE N. O. NELSON MANUFACTURING COMPANY, OF SAME PLACE.

DESIGN FOR A VALVE FOR BASINS AND BATH-TUBS.

SPECIFICATION forming part of Design No. 21,933, dated October 25, 1892.

Application filed March 1, 1892. Serial No. 423,429. Term of patent 14 years.

To all whom it may concern:

Be it known that I, WILLIAM H. GRAHAM, of St. Louis, Missouri, have invented and produced a new and original Design for Valves for Basins and Bath-Tubs, of which the following is a specification, reference being had to the accompanying drawing, which exhibits the newly-designed valve from the front in perspective.

10 The leading feature of my design consists in the domed body, which, generally considered, constitutes the lower two-thirds of the structure.

15 The body *a* of the valve, which in use rests upon the slab *b* or other support, is extended in a transverse direction to form a part whose width is greater than its height and also than its depth, and from its upper end downward about half-way to its lower end the body continues about the same size and shape, and its 20 lower end curves downward and outward to form a base somewhat larger than the upper portion of the body. The contour of the body is substantially a combination of curved surfaces. The upright surface is largely con-

cave to the view; but beneath the nozzle a convexity *f* appears, terminating at the support *b* and causing the outline of the lower end of the body to be scalloped at *g g*. The dome *h*, which is spherical in appearance, rests 30 centrally upon the body. A cup *i* serves to complete the design. Its general dimensions accord with those of the body, being longer transversely and in height about equal to that of the body or of the dome—that is, 35 viewed as a whole, the body, dome, and cup in a vertical direction are substantially equal in prominence, and, it may be added, the structure in a general aspect has the appearance of a cup whose base or foot is the body 40 *a* and whose stem is the dome *h*.

What I claim is—

The design for a valve for basins and bath-tubs, as herein described and shown.

Witness my hand this 25th day of January, 45 1892.

WILLIAM H. GRAHAM.
